UNITED STATES PATENT OFFICE.

ROBERT M. DILLON, OF PHILADELPHIA, PENNSYLVANIA.

DESIGN FOR AN EYE-SHIELD.

46,872.

Specification for Design.

Patented Jan. 26, 1915.

Application filed September 30, 1914. Serial No. 864,363. Term of patent 14 years.

To all whom it may concern:

Be it known that I, ROBERT M. DILLON, a citizen of the United States, residing at Philadelphia, in the county of Philadelphia and State of Pennsylvania, have invented a new, original, and ornamental Design for Eye-Shields, of which the following is a specification, reference being had to the accompanying drawing, forming a part thereof.

Figure 1 is a perspective view of an eye

shield, showing my new design. Fig. 2 is a perspective view looking at the design at a different angle from that shown in Fig. 1.

I claim:

The ornamental design for an eye shield, as shown.

ROBERT M. DILLON.
